CUT, A CORPORATION OF CONNECTICUT.

BUTTON-SETTING MACHINE.

1,183,823.

Specification of Letters Patent.

Patented May 16, 1916.

Original application filed May 10, 1915, Serial No. 27,042. Divided and this application filed November 13, 1915. Serial No. 61,326.

To all whom it may concern:

Be it known that we, FREDERICK E. STANLEY and GEORGE R. LEGGETT, citizens of the United States, residing at Waterbury, in the county of New Haven and State of Connecticut, have invented a certain new and useful Improvement in Button-Setting Machines, of which the following is a full, clear, and exact description.

10 This invention relates to a power machine for setting tack-fastened buttons on garments and other articles rapidly and accurately, and more particularly to mechanism forming a part of such a machine for presenting the buttons in proper position and relation to the tacks for setting the buttons on an article.

This case is divided out of our application for patent for button setting machines, 20 filed May 10, 1915, Serial No. 27,042, in accordance with the requirement of the Patent Office.

In all prior button setting machines of this type known to us, the buttons are presented to the setting mechanism by means of an inclined raceway down which they slide bottom-side up and in which they are righted by means of a reverse bend in the raceway. But this method has many disadvantages, among which are the following, 25 viz., that the buttons sometimes jam in the raceway when they come to the reverse curve; and that gravity being depended upon to right the buttons, the feed is not always rapid enough to meet the requirements 30 of the machine, so that at times a tack is presented with no button to which to apply it.

The object of this invention is to provide 40 mechanical means for righting the buttons which does not depend upon gravity except for the initial presentation of the buttons to it from a chute or raceway in which the buttons run bottom-side up and in a straight line, whereby the above mentioned disadvantages of previous constructions are done away with and an increase in speed in the setting operation of the machine and the 45 number of buttons that may be set per minute by the machine, is obtained.

The invention consists in what we will herein call a "button turner" adapted to re-

ceive the buttons edge up and one at a time from a raceway connected with a hopper, and to turn them into proper position for 55 application of the tack to affix the buttons to the article to which they are to be applied, and in means for driving the parts, as we will proceed now to explain and finally 60 claim.

In the accompanying drawings illustrating the invention, in the several figures of which like parts are similarly designated, Figure 1 is a front elevation of a complete machine embodying the device of this invention. Fig. 2 is a left-hand side view of the upper part of the machine. Fig. 3 is a horizontal section below the magazines or hoppers, on a larger scale. Fig. 4 is a perspective view of the button righting device. 70 Fig. 5 is a side elevation of part of the bearing for the button righting device open to gain access to such device. Fig. 6 is a perspective view of the button righting cylinder and the button ejector separated. Fig. 75 7 is a vertical section taken to the right (Fig. 1) of the setting mechanism and on a larger scale. Fig. 8 is an inside elevation of the button holder, and Fig. 9 is a side elevation of one of the two fingers of the button holder. Fig. 10 is a sectional elevation of the tack holder and plunger. Fig. 11 is a vertical section taken in the plane of line A. B, Fig. 3, looking toward the right, but showing the parts in position when the button has been set. Fig. 12 is an edge view or elevation of one form of button which the machine shown is designed to set; Fig. 13 is an elevation of a fastening tack, and Fig. 14 is a cross-section of a button set on a piece 80 85 90 of fabric.

1 is a bed-plate or table, mounted upon legs or frames 2.

3 is the main-shaft from which the various moving parts are driven. This shaft 95 may be and preferably is connected with a drive-shaft 4 by reducing gearing 5 and 6 for the purpose, among others, of running the machine at high speed. The shaft 4 is provided with any suitable means preferably a band-pulley 7, for application of power by means of a round belt 8. The shafts 3 and 4 are mounted in bearings in a head 9 erected on the bed-plate or table 1,

and the gear 5 is arranged loosely upon its shaft 3 with any suitable friction or other clutch (not shown) interposed between the shaft and gear and operated by any suitable means to cause the gear to turn with the shaft, as by a lever 10 pivoted on stud-shaft 11 mounted in boss 12 on the head, and connected with a treadle 13 by a rod 14, but other suitable means may be used for starting and stopping the machine instantly.

The driven parts of the machine derive motion from the main-shaft, as will appear more fully in the progress of this description, and we have found that the high speed required and the necessary control of the machine are best obtained by applying the power by what is commonly called a round belt not directly to the main-shaft 3 but to a driving shaft 4, and gearing these shafts by a two to one or other desired train of gears 5, 6, the main shaft having the stopping and starting mechanism applied to it.

The button magazine or hopper 15 and the tack magazine or hopper 16 are mounted upon the head in any suitable manner, and at any suitable angle, and so as to be capable of being turned to effect the discharge of their contents. Preferably these magazines have their shafts 17 and 18 respectively extended rearwardly and supplied with band-pulleys 19 and 20 respectively, which are fast on their shafts and are connected by the band 21, so as to turn in the same direction. The shaft 17 is driven by a pulley 22 connected by a band 23 passing over direction idlers 24 and 25 to a driving pulley 26 on the main-shaft. The pulley 22 is loose on shaft 17 and carries a pawl 27 which engages a ratchet 28 fast on shaft 17. The button hopper or magazine is loose on its shaft but is held frictionally to turn with it by any suitable means, such as the spring 29 and the washers 30, which latter are keyed to turn with the shaft and the nut 31. By these means the button and tack magazines may be turned by hand, independently of the driving pulley 22, so as to remove obstacles and provide for emergency filling, and the filling of the raceways leading from the magazines to the setting devices, whenever they become empty or insufficiently filled. The tack hopper may be secured to its shaft in any suitable way to turn with it as desired, and we have shown a nut 32 as the means for retaining it upon its shaft.

The buttons are discharged from the magazine into a raceway 33 depending therefrom, with their hubs outermost, and must be turned for setting purposes, so as to present their hubs lowermost and vertically. The lower end of the raceway is intercepted transversely by a reciprocating cut-off 34, actuated by a rock-lever 35 pivoted on the head of the machine, a connecting link 36, a spring 37 and a cam 38 on the main shaft,

to deliver one button at a time, and below this cut-off is an offset raceway 39 which opens into a transversely arranged casing 40, in which is arranged the button-turner that receives the button edgewise from the race-way and gives it a quarter turn so as to present its hub vertically downward. This turner comprises a cylindrical piece 41, having a diametrical opening or slot 42 at one end, of a size sufficient to receive the button edgewise, and it is provided with circumferential spur-teeth 43 outside of the casing which are engaged by a toothed rack 44 on a longitudinally reciprocating bar 45 mounted in the head of the machine at the rear of the turner and actuated by a cam 46 on the cam-carrier 47 fast on the main shaft, and a spring 48. By this means the turner is turned with its opening vertical to receive a button edgewise from the race-way and then it is turned a quarter turn so as to move the button from a vertical to a horizontal position with its hub down and in the position it must have in order to be set. The turner piece 41 is bored longitudinally and in this bore is mounted a stem 49 having the transverse head 50 curved on its face to conform to the curvature of the rim of the button-head. The stem projects out of the toothed end of the turner device and its head works in the opening or slot 42. The stem is provided with an adjustable grooved collar 51 which is engaged by a tracker pin on a shifter lever 52 pivoted on the head of the machine and having a cam roller engaged by a cam 53 on the main shaft, so that when the machine is running the stem and its head will be given a longitudinal reciprocating movement in the turning device to eject the turned or righted button therefrom, and because of this function the stem and its head are herein referred to as an ejector. The cams 38 and 53 may be and are here shown as one structure. In order to obtain access to the turner to remove a defective button and for other purposes, the bottom of the casing is made with a hinged gate 54 provided with a pivoted spring or other effective latch 55 engaging a slotted keeper projection 56 on the casing,—see Figs. 4, 5 and 7, for details.

By means of the button-turner or button-righting device described, the positioning of the button is removed from the uncertain automatic action of the prior art raceways, to a certain and positively acting mechanism, with the result, among others, that the speed or capacity of the machine is greatly increased, and its operation attended by relatively few misplaced or improperly set buttons.

The buttons are delivered, one at a time, to the spring closed fingers 57, mounted upon the side of the head and having their lower ends 58 turned toward the turner last de-

scribed. These fingers are hinged together at their upper ends so as to be capable of parting or separating at their inturned lower ends to permit the movement therethrough 5 of the vertically reciprocating setting anvil 59 and the discharge therefrom of the button being set, and these fingers are held in operative relation by a spring 60. The in-turned ends of the fingers are undercut at 10 their outer portions transversely to the vertical anvil passage, to form a pocket 61, of substantially the profile of the button, into which the buttons are successively ejected by the ejector, and by means of this pocket 15 the button is held in the fingers against the possibility as well of misplacement as of accidental displacement. The fingers are held in longitudinally sliding engagement with the head by a screw 62, the head of which 20 is large enough to overlap the fingers at their greatest lateral separation in operation. The upper portions of the fingers are cut away to form an intermediate slot 63 and into this slot projects a pin 64 fast on the anvil. 25 Above the pin is an adjustable spring adjusting device 65 on the fingers, to adjust the finger-ends to the turner and take up any shock. The anvil 59 in its descent comes into contact with the finger-ends and carries 30 said fingers down with it until said fingers reach the limit of their downward movement, which is determined by the relation of the screw 62 to the slot 66 between the fingers in which it is arranged. The finger- 35 ends are moved by the anvil into a position lower than that of the turner, and then the further descent of the anvil and its consequent ejection of the button cams the fingers apart under resistance of their spring, 40 and the button is in position to be set. After the button is set the anvil is retracted and as it rises and the pin 64 comes into engagement with the adjusting device 65, the fingers are returned to normal button-receiving 45 relation to the turner and ejector. This return movement of the fingers is arrested by the bottom of the slot 66 coming into contact with the emergency finger-opening cam lever 67. This cam-lever 67 is pivoted to 50 the head so as to operate within the slot 66 to separate the fingers whenever desired. When in this position the turner opening or slot 42 is in horizontal alinement with the pocket 61 in the finger-ends and the ejector 55 is in position to eject the button from the turner into the pocket in the fingers.

The anvil may be operated by any suitable means, such as a bell-crank lever 68 mounted in the head and connected with the 60 anvil by a link 69, the lever 68 being actuated by a connecting rod 70 extending thence rearwardly and forked to straddle the main shaft and having a cam-roller 71 engaged by a cam 72 fast on said main shaft which im- 65 parts a compound longitudinal and rising

and falling motion to the connecting rod and a rocking motion to the bell-crank lever 68.

The tack magazine has a raceway 73 made with a twist so as to receive the tack heads 70 on edge from the magazine and turn the tacks point up before they reach the cut-off 74. This cut-off has two fingers 75 having their tips 76 extending toward one another across the raceway, and these fingers are fast 75 on a rock-lever 77 pivoted on the back of the raceway and connected by a rod 78 with a vibrating arm 79 pivoted at 80 to the head and having a cam-roller 81 engaging a cam 82 fast on the main shaft. In order to prevent breaking of parts in the event of jamming the raceway or cut-off, the rod 78 has a coil 83 formed in it to serve as a spring which will yield under such jamming and thus prevent breaking any of the parts. The 85 rock-lever 77 and its fingers 75 may be returned to position by a spring 84 fastened to said lever by one end and to the head by the other. The tacks are delivered one by one to a feed trough 85 arranged in the head 90 beneath and in line with the anvil, and in this feed trough is a tack ejector 86 of the kind shown in the parent case referred to. This tack ejector is reciprocated in the feed-trough by means of a bell-crank lever 87 95 pivoted on the machine head and having one arm connected by a link 88 with an upstanding lug 89 on the ejector, and another arm provided with a cam-roller 90 engaging a cam 91 fast on the main shaft. The tack 100 ejector delivers the tack to fingers 92 pivoted to the head adjacent to the setting die or plunger 93, these fingers being yieldingly connected, as by a bow spring 94. A stop 95 prevents the escape of the tack and also 105 serves to position it on the plunger.

The plunger 93 is vertically reciprocated in the head and between the yielding fingers 92 by a bell-crank lever 96 pivotally mounted in an extension of the head beneath the 110 bed-plate 1, and connected with the plunger by link 97, and having a connecting rod 98 provided with a forked end which straddles the main shaft and is provided with a cam roller 99 engaged by a cam 100 fast on the 115 main shaft.

We have herein referred to the cams 82, 91 and 100 as though each were a separate structure, as they may be, but they are herein shown as combined in one structure. 120 These and other details of construction and operative parts are variable at the pleasure of the machine builder, so long as the effective co-operation and coördination of parts are concerned and the principle of the invention followed. Again, it is to be noted that we have described the button turner in broad terms, in order to emphasize the fact that we do not wish to be considered as limiting our 125 invention to details. In the drawings, how- 130

ever, one construction only is shown, and this illustrates the cylindrical piece 41 as having a reduced portion 101 next to the teeth 43 and fitted in a sleeve 102 having a 5 rear extension 103 fixed to the back of the casing, as by screws 104. This cylindrical piece is held in the casing and sleeve by the collar 105 fixed to the reduced portion 101 outside the sleeve. The casing in this 10 instance is a part of or attached to the lower end of the button raceway. The teeth 43 may be cut in the piece 41 as shown, or otherwise provided.

The operation would appear to be sufficiently indicated in and by the foregoing. However, it may be briefly stated that the respective magazines being supplied with buttons and tacks and the machine started, the buttons and tacks are fed one by one to 20 their respective delivery points. The article to be supplied with buttons, represented at 106, Fig. 14, is passed by the operator between the anvil and plunger and arrested momentarily beneath the anvil. The tack 25 107 is first positioned over the plunger, point up, and held by the fingers 92, and the tack ejector recedes to take its place for the next tack. Then a button 108 is righted, transferred to the pocket in the fingers 57 and 30 carried down by the fingers and anvil toward the tack and the plunger is caused to ascend and pass the tack point through the article and into the combined anvil and filler 109 in the button wherein it is clenched and the 35 button so set. Then the parts reverse, the article is moved along to a point where another button is to be attached, and the operations repeated. The spring fingers 92 yield in the direction of movement of the 40 article and thus offer no obstacle to the release of the set tack, but rather facilitate it.

As already sufficiently indicated, the invention contemplates such changes as will meet the requirements of the user, the kind 45 or type of button to be set, and the kind or type of tack or fastener.

The claims for the combination of the button supplying means, the tack supplying means, and the mechanism for bringing the 50 buttons and tacks into setting relation and for setting the buttons, form the subject of the parent application hereinabove mentioned, and the claims for the mechanism for acting upon the tacks form the subject 55 of our concurrent divisional application of even date, Serial No. 61,327.

What we claim is:—

1. In a button setting machine, a button turner adapted to receive the button from a 60 suitable source of supply, means to turn over said turner and its contained button and thereby present the button aright for the subsequent application of the fastening device, and an ejector mounted on the turner

in permanent alinement with its discharge 65 end for discharging the thus righted button from the turner.

2. In a button setting machine, a button turner adapted to receive the button from a suitable source of supply, means to turn over 70 said turner and its contained button and thereby present the button aright for the subsequent application of the fastening device, and means carried by and operating within the turner to eject said button from 75 the turner.

3. In a button setting machine, the combination with a button magazine and a raceway for conducting the buttons therefrom, of a rotary reciprocating button turning device intercepting the raceway at its delivery 80 end and adapted to turn the buttons one at a time right side up, and a longitudinally reciprocating ejector carried by and operating within the turner.

4. In a button setting machine, the combination of a magazine button feed, including a delivery raceway in which the buttons feed edgewise, means to receive and right the buttons arranged transversely at the delivery end of the raceway and including a cylinder having a diametrical opening at one end into which the buttons fall, spur-teeth on the cylinder, a toothed rack engaging said teeth to turn the cylinder a quarter 95 turn to change the position of the button and means to actuate the rack.

5. In a button setting machine, the combination of a magazine button feed, including a delivering raceway in which the buttons feed edgewise, means to receive and right the buttons arranged transversely at the delivery end of the raceway and including a cylinder having a diametrical opening at one end into which the buttons fall, spur-teeth on the cylinder, a toothed rack engaging said teeth to turn the cylinder a quarter turn to change the position of the button, an ejector arranged in and carried by the cylinder and having a head in the opening 100 therein and a stem projecting outside of the cylinder, means to actuate the rack, and means to reciprocate the ejector.

6. In a button setting machine, a button turner adapted to receive the button from a 115 suitable source of supply, means to turn over said turner to right the button for subsequent presentation to the fastening device, a casing in which the turner is mounted, and a gate in the casing for obtaining access 120 to the turner.

7. In a button setting machine, the combination with a button magazine, a main raceway leading therefrom, an auxiliary raceway arranged at the delivery end of the 125 main raceway and offset therefrom, a cut-off interposed between these raceways, a casing arranged at the discharge end of the

- auxiliary raceway and communicating therewith, a transversely slotted cylinder arranged in said casing opposite the discharge end of the auxiliary raceway and adapted to receive a button edgewise therefrom, means to turn said cylinder and its contained button a quarter turn, and means to eject the thus turned button.
8. In a button setting machine, a button feeding mechanism, a shaft on which it is loosely mounted, means to frictionally engage the shaft and button feeding mechanism, a driven pulley loosely mounted on the shaft, a driving pulley fast on the shaft, and means interposed between the driven 15 pulley and the driving pulley to effect the turning of the shaft at pleasure.
9. In testimony whereof we have hereunto set our hands this 10th day of November A. D. 1915.
10. In a button setting machine, a shaft on which it is loosely mounted, means to frictionally engage the shaft and button feeding mechanism, a driven pulley loosely mounted on
